UNITED STATES PATENT OFFICE.

JOSEPH J. BISEL AND JOSEPH HANCOCK, OF PHILADELPHIA, PENNSYLVANIA.

CLOTHES-DRIER.

SPECIFICATION forming part of Letters Patent No. 562,351, dated June 16, 1896.

Application filed April 4, 1896. Serial No. 586,187. (No model.)

To all whom it may concern:

Be it known that we, JOSEPH J. BISEL and JOSEPH HANCOCK, citizens of the United States, residing at Philadelphia, in the county of 5 Philadelphia and State of Pennsylvania, have invented certain new and useful Improvements in Clothes-Driers, of which the following is a specification, reference being had therein to the accompanying drawings.

10 Our invention relates to an improved clothes-drier of that class in which an arm-carrying frame or bench is secured to a carriage adapted to be elevated or lowered upon a staff.

15 The invention consists in certain details of construction and combinations of parts, which will first be described in connection with the accompanying drawings, and then pointed out in the claims.

20 Figure 1 of the drawings is a side elevation of our improved clothes-drier, parts of the staff and operating-rope being broken out. Fig. 2 is a perspective view of the bench, detached, one of the clothes-arms being shown 25 in operative position and another shown in dotted lines in the position it occupies when not in use. Fig. 3 is a broken plan view of portions of the bench with a clothes-arm in place, showing the locking-plate in a position 30 to permit the release of the clothes-arm, a portion of said plate being shown in dotted lines to illustrate the manner of its attachment to the bench. Fig. 4 is a transverse sectional detail view of the cam mounted in its 35 casing.

Referring to the drawings, A is a staff, preferably of wood, designed to be attached to the wall of a room by means of brackets B and C, which are secured to the respective ends of 40 the staff, as shown.

D represents a carriage, which is a hollow block, rectangular in shape, and of a size to encompass the staff A. This block is bifurcated on each side at both the upper and 45 lower ends, as at 1, to receive rollers 2, journaled on pins 3, passed through the respective branches of the bifurcations. By this construction the carriage has roller-bearing on all sides of the staff.

50 E represents a bench, comprising a triangular-shaped arm-holding plate e and a sup-

porting-rail e'. Formed integral with the rear side of plate e is a rectangular sleeve 4, designed to fit snugly around the carriage D, and to be removably secured thereto by two 55 or more screws 5. Formed in plate e, near to and in alinement with its converging sides, are a number of parallel slots 6, and around the outer edge of said plate is formed a narrow vertical rim 7. A pulley 8 is centrally 60 mounted in plate e. The supporting-rail e' is shaped to conform to the general direction of the converging sides of plate e, and is connected to said plate by connecting-pieces 9. This rail is of such size and so positioned that 65 its upper side will lie in a lower horizontal plane than plate e and in a vertical plane just far enough forward of the rim 7 of the plate to permit the clothes-arms when not in use to hang between the rim and rail, as shown. 70

F represents two locking-plates, which are each movably secured to plate e by two pins 10, fixed in the locking-plate and passed through slots 11 in plate e, their lower ends being headed, as shown in dotted lines in Fig. 75 3. Each locking-plate is so positioned on plate e that its forward edge will partially overlap the slots 6; and in this edge of the locking-plate are formed recesses 12, which, by a proper movement of the said plate, are 80 made to register with the slots 6 in plate e; but on a reverse movement of the locking-plate these recesses pass beyond the slots 6, thus covering the rear portions of said slots. 85

From the forward edge of rail e' projects a rectangular casing G, open on one side, and having near the open side a forwardly-projecting flared finger 13. Opposite the open side of casing G, and projecting from rail e', is an arm 14, which extends past the open side 90 of the casing and has its outer end flared at 15, forming, with the finger 13, a flared entrance for the elevating-rope.

In the casing G is mounted a cam g, having a lip 16 depending from its forward side. A 95 portion of the cam is serrated, as at 17, but the face of the lip portion is plain. The object of the cam of this construction is to adapt it to hold a small elevating-cord as well as a Manila rope. It is apparent that the serrated 100 portion of the cam will effectually hold the ordinary rope; but if a small soft-woven cord

were used that portion of the cam would soon render the latter useless, for the reason that the ridges would cut into the cord. To prevent the ridges from contacting with a small 5 cord, the cam is so pivoted that they will swing clear of it, when the plain face of the lip will engage it firmly, and no compression of the cord thereby will permit the cam to revolve far enough to release the cord, as the 10 lip will contact with arm 14.

H is a clothes-arm, of any suitable length, and provided near one end with an L-shaped hook 18. The arm (of which there may be any suitable number) is placed in position by 15 passing its hook 18 through one of the slots 6 and moving it forward until it contacts with the front wall of the slot, in which position the hook rests on the plate e, and the arm rests on and is supported by the rail e', as 20 clearly shown in Figs. 2 and 3. Now by moving the locking-plate longitudinally its recesses 12 are moved out of register with the slots 6, thus presenting a solid line of metal to the rear of the hook 18 and preventing its 25 accidental withdrawal. When the arm is not desired for use, the locking-plate is moved until its recesses 12 again register with the slots 6, thus permitting the hook to be removed from the slot, when it may be hung 30 over the rim 7, the arm hanging down between the plate e and the rail e', as shown in Fig. 2, whereby the arm or arms in the pendent position will be held snugly in place.

I is an elevating-rope, one end of which is 35 secured to the bracket B, then carried down and around pulley 8 on plate e, and then up and around a pulley 19, mounted in bracket B, the free end of the rope hanging down. By this construction the operator by pulling 40 on the rope I will elevate the carriage and its accompanying parts, and when the car-

riage is sufficiently elevated the free end of the rope is placed in the casing G between the cam g and the arm 14 on the supporting-rail, when the weight of the bench and the 45 articles thereon will cause the same to impinge the rope and hold it securely in the casing, thus preventing accidental lowering of the parts.

Having thus described our invention, what 50 we claim as new, and desire to secure by Letters Patent, is—

1. In a clothes-drier, a bench having a series of slots, in combination with a series of clothes-arms each provided near one end with 55 a hook, said hooks being adapted to pass through the slots in the bench, and a locking-plate overlying the rear portions of the slots and having recesses in its forward edge normally registering with the slots, said plate 60 being adapted to be moved longitudinally, whereby the recesses are thrown out of register with the slots and the arm-hooks thereby locked in the latter.

2. In a clothes-drier, a bench comprising a 65 slotted arm-carrying plate and an arm-supporting rail, in combination with a series of clothes-arms, each having a hook near one end, the hooks being adapted when the arms are in use to engage with the plate through 70 the slots therein, said plate having a vertical rim on its forward edge, and the rail being so positioned with relation to the plate that the arms when not in use may hang from the rim and be held thereon by the rail. 75

In testimony whereof we affix our signatures in presence of two witnesses.

JOSEPH J. BISEL.
JOSEPH HANCOCK.
